DESIGN FOR AN ELECTRIC REFRIGERATOR

Stephen E. Ponticos, Norwood, Ohio

Application October 14, 1933, Serial No. 49,490

Term of patent 3½ years

To all whom it may concern:

Be it known that I, STEPHEN E. PONTICOS, a citizen of the United States, residing at Norwood, in the county of Hamilton and State of Ohio, have invented a new, original, and ornamental Design for Electric Refrigerators, of which the following is a specification, reference being had to the accompanying drawing, form-

ing part thereof, of which the figure is a perspective view of an electric refrigerator, showing my new design.

I claim:

The ornamental design for an electric refrigerator, as shown.

STEPHEN E. PONTICOS.
